MACHINE FOR CUTTING, FORMING AND INSERTING LEADS OF ELECTRICAL COMPONENTS

Lawrence E. Mueller, Livonia, Mich., assignor to Burroughs Corporation, Detroit, Mich., a corporation of Michigan

Filed Dec. 5, 1962, Ser. No. 242,409
6 Claims. (Cl. 1—322)

This invention relates generally to machines for severing, forming and inserting leads of components and particularly to applicators for applying electronic components to circuit supporting boards.

In the manufacture of electrical units of the type having electronic components mounted on circuit boards, it has been the practice to apply the components to the board by means of a mechanical applicator. Usually the components are fed singly by an indexing mechanism onto coplanar shear blocks and a former block where oppositely directed conductors of the components are sheared to the desired lengths, then bent into relative parallel relationship, and thereafter inserted into pre-punched holes in the circuit board. To perform the above mentioned operations, pairs of tools including cutting tools, bending tools, and drivers are employed and the tools of said pairs must be accurately spaced apart, the spacing being determined by the size of the components, or specifically the lengths of the component bodies. These applicators are satisfactory in operation, but have the objection that a separate applicator is required for handling each different size of component of which there are a great many sizes in use today. In addition, insofar as I am aware there are no devices of the above mentioned type capable of severing, bending and inserting tipped leads into circuit boards.

Accordingly, it is the principal object of the invention to provide an improved electronic component applicator that is adaptable to handle a run of components of one size and be readily adaptable to handle a run of components of another size.

Another object of the invention is to provide an electronic component applicator of a structural character such that it can be used to apply a run of electronic components of any size within predetermined limits.

Specifically, it is an object of the invention to provide an applicator of the above mentioned character which is readily adjustable and certain parts readily interchangeable to handle any size component within a predetermined range of sizes.

In connection with the next preceding object, it is an object of the invention to provide an improved applicator for bending and inserting leads in which the bending tools are displaceable by inserting tools to allow the latter to travel in the same path as the former.

A further object of the invention is to provide an improved machine for severing, bending and inserting tipped component leads.

Other objects of the invention will become apparent from the following description, taken in connection with the accompanying drawings in which:

FIG. 1 is a side view partly broken away and in section of a machine including an electronic component applicator embodying features of the invention;

FIG. 2 is a front view of the applicator shown with certain parts removed and the operating parts in their retracted or home positions;

FIG. 3 is a view similar to FIG. 2, showing the operating parts in the positions they will assume at the completion of the application of a component;

FIGS. 4 and 5 are similar fragmentary sectional views,

2

showing certain operating parts in different positions of operation;

FIG. 6 is a vertical sectional view, taken along the line 6—6 of FIG. 4;

FIG. 7 is a vertical sectional view, taken along the line 7—7 of FIG. 5;

FIG. 8 is an elevational view, taken in the direction of the arrows 8—8 of FIG. 1;

FIG. 9 is a horizontal sectional view, taken along the line 9—9 of FIG. 8;

FIG. 10 is a vertical sectional view, taken along the line 10—10 of FIG. 9;

FIG. 11 is a fragmentary side view of one of the operating parts of the applicator;

FIG. 12 is a vertical sectional view, taken along the line 12—12 of FIG. 2;

FIG. 13 is a side view of an indexing mechanism for feeding electronic components to the applicator;

FIGS. 14, 15 and 16 are vertical sectional views similar to FIG. 12, showing the operating parts in various positions;

FIG. 17 is a cross sectional view, taken along the line 17—17 of FIG. 12;

FIG. 18 is a cross sectional view, taken along the line 18—18 of FIG. 12;

FIG. 19 is a cross sectional view, taken along the line 19—19 of FIG. 18;

FIG. 20 is a fragmentary vertical sectional view, taken along the line 20—20 of FIG. 18, and

FIG. 21 is an exploded perspective view of the operating and other parts of the applicator.

Referring to the drawings by characters of reference and first to FIG. 1, the apparatus shown includes a standard 20, an electronic component applicator 22, feed devices 24 to feed electronic components singly to the applicator and a power element, or air cylinder 26 to actuate the applicator. The standard 20 has a bed or anvil 28 to support a circuit board 30, and the applicator 22 and the feed devices 24 are mounted on the standard, the applicator being directly above the anvil and the feed devices being mounted directly on the applicator.

The electronic components, as at 34, are individually contained within casings which are usually cylindrical and each has a pair of externally projecting leads or conductors 36 which project, one from each end of the casing or in opposite directions. These components 34 are attached to and span a pair of disposable spaced apart parallel belts 38 for conveniently feeding them to the applicator 22, the components being attached by their conductors 36 to the belts as shown in FIG. 8. The belted components 34 are wound on a supply reel 40 which is preferably mounted on a bracket 42 above the applicator 22. A guideway, designated generally by the numeral 44, guides the belted components 34 downwardly to the component feed device 24 which feeds the components to the applicator 22 in a manner hereinafter described. Attached to each of the component conductors 36, equidistant from adjacent ends of the component casings, are wedge shaped triplets 46 to be inserted and wedged into holes 48 provided in the circuit board 30 so as to hold the components in place for a subsequent soldering operation. The triplets 46 are applied to the component conductors 36 by a separate operation performed prior to the belting of the components.

The applicator 22 has a sectionally constructed supporting or mounting means for mounting the applicator on a horizontal arm 49 of the standard 20, the mounting means comprising an upper sleeve 50 and a lower supporting member 52. The sleeve 50 is received and tightly clamped in a split clamp 54 provided on the end of the standard arm 49, and the supporting member 52 depends

from the sleeve and is secured thereto by bolts 56, the supporting member preferably being a channel structure having vertical sides 58 and a connecting web 60, as is shown more clearly in FIG. 17.

Fitting snugly within the channel mounting member 52 there is a vertically elongated open ended body 62 which may be rigidly secured to the mounting member by screws 63. As shown in FIG. 17, the body 62 is of rectangular cross section and may comprise opposite side plates 64, a rear plate 65 and a removable front plate 66, suitable secured together, such as by means of screws. Mounted on the outer side of the front plate 66, as shown in FIG. 1, there is a cast bracket 70 having a pad or plate 72 which is rigidly secured flat against the body front plate 66 by screws 74, FIG. 12. In a plane, at an acute angle to the pad 72 are the faces of bosses 76 of the bracket 70 to which is secured a plate 78 which, in part, forms the guideway 44, the plate being secured by screws 79 to the bosses. A second and readily removable plate 80 is positioned flat over the fixed plate 78, the opposed faces of the plates being recessed to define the belt guideway and the component guideway, shown in FIG. 9. As shown in FIGS. 8 and 9 a pair of clamps 82, pivoted to the fixed guide plate 78, are provided to clamp the guide plate 80 to the guide plate 78, the plate 80 being retained against downward movement by dowel pins 84 which also serve to locate the plate for assembly.

Slidably guided vertically in the body 62, the applicator has a vertically reciprocal actuator and carrier 86 in the form of a driver bar of rectangular cross section. The driver bar 86 extends upwardly into the sleeve 50 wherein it is connected by a universal ball joint 88 to the lower end of a connecting rod 90. The upper end of the connecting rod 90 is pivotally connected to one arm of a lever 92 which, as shown in FIG. 1, is pivoted on the standard 20, as at 93. Another arm of the lever 92 is pivotally connected by a clevis 94 to a connecting rod 96 which in turn is connected to the piston of the power element or air cylinder 26. In the present instance, the air cylinder 26 is pivoted at its lower end, on a shaft 98 that is fixed at its opposite ends in and to the sides of the standard 20. An air port 99 in the end of the air cylinder 26 serves as the air inlet and outlet and is connected by a tube or pipe 100 to a fitting 102 of a solenoid valve 104 for connection to a source of compressed air and to an outlet or bleed 106 to atmosphere. A switch 108 controls energization of the solenoid valve 104 and may be a manually operable switch, or a time operated switch, as desired. In either case, it will be apparent that when the switch 108 is closed, the solenoid 104 will be activated and the piston of air cylinder 26 will be forced upwardly to move the driver bar 86 downwardly.

Positioned within the body 62 and forming a vertical guideway therein there is a pair of rectangular plates 110 which are in broadside relationship respectively to the inner faces of the body side plates 64. The plates 110 are respectively supported on the body side plates 64 by vertically spaced horizontal pins 112 which are secured in and to the body plates 64 and extend through aligning apertures 114 in the plates 110 to allow for broadside movement of the latter toward and away from the body side plates 64. At the lower ends thereof, the plates 64 and 110 have their opposed surfaces recessed to receive a pair of pinions 116 which are journaled on the plates and constitute part of the feed device for feeding the electronic components 34 singly onto a shear block supporting member or bracket 118, positioned below the lower end of the body 62. The teeth of the pinions 116 engage between the parallel conductors 36 of the belted components 34 to advance the latter to the supporting member 118.

A pair of cutter carrying reciprocal slide members 120

are provided to cut the component leads 36 to the desired lengths and are slidably guided vertically within the body 62. The slide members 120 are respectively positioned flat against the opposed faces of the plates 110 for sliding contact therewith and are operatively connected to the driver bar 86 by a clutch comprising a vertically slidable block 122 and a clutch member or ball 124. The clutch ball 124 is retained in an aperture in the clutch block 122 and is movable laterally to connect and/or disconnect the slide members 120 and the driver bar 86. By reference to FIG. 12, it will be seen that the diameter of the clutch ball 124 is greater than the thickness of the wall of clutch block 122 and that the driver bar 86 has a recess or socket 128 to receive the ball so as to connect the clutch block 122 releasably to the driver bar 86. Normally the clutch ball 124 is engaged in the socket 128, as shown in FIG. 12, the term "normally" referring to the "home" or "up" positions of the operating parts of the applicator. Below the clutch block 122, the body rear plate 65 is provided with an upwardly facing internal shoulder 130 which functions as a stop for the clutch block and thus limits the downward movement of the slide members 120. After the clutch block engages its stop 130, continued downward movement of the driver bar 86 forces the ball 124 into a clearance recess 132 provided in the inner face of the body rear plate 65.

The slide members 120 are connected to the clutch block 122 in a manner such that they may be movably adjusted toward and away from each other while remaining operatively connected to the clutch block 122. To accomplish this, the upper ends of the slide members 120 are provided with laterally inwardly directed connectors or tabs 125 which engage in a horizontal slot 126 in the clutch block 122. At their lower ends the slide members 120 are provided with suitable cutters 133, preferably having V-notched cutting edges, as shown.

Mounted on the body 62 at the lower end thereof is the shear block supporting member 118 having a vertical leg 134 and a pair of laterally positioned horizontal legs 136. The vertical leg 134 lies flat against the body rear plate 65 and may be rigidly secured thereto by screws, or by other suitable means. The horizontal legs 136 extend forwardly beneath the lower ends of the body 62 and below and just outwardly of the cutters 133, the legs having transversely keyed ends to receive transversely aligned shear blocks 138. End clamping blocks 140, also keyed to the shear blocks 138, are tightened down by screws 142 which pass through elongated apertures 144 in the shear blocks to allow for adjustment of the blocks 138 to positions to shear conductors of different sizes of components. The inner edges of the shear blocks cooperate with the cutters 133 to shear the component conductors 36 to the desired lengths.

Positioned within the body 62 there is another pair of spaced apart reciprocal slide members 148 carrying respectively on their lower ends, a pair of forming or bending tools 150 cooperable with an anvil or forming block 151 to bend down end portions of the component leads 36 after the latter have been severed. The forming block 151 is positioned below the lower end of the driver bar 86 and the bending tools 150 are laterally positioned so that on descent they straddle the forming block along opposite sides thereof to bend end portions of the leads 36 downwardly in parallel relationship in axial alignment with holes in the circuit board 30. The bending tools 150 travel in spaced apart paths of travel or vertical planes indicated by the dot and dash lines 152, FIGS. 4 and 5. Opposed faces of the bending tools 150 are provided with vertical slots 149 to receive and retain the leads 36 against internal movement, the components being held to the bending tools 150 frictionally by the tension established in the leads as a consequence of the bending operation.

The pair of tool carrying slides 148 are respectively positioned flat against the opposed sides of the cutter slide members 120 and are operatively connected to the reciprocal driver bar 86 by a clutch which, like the previously described clutch, includes a reciprocal clutch block 154 and a clutch member, or ball 156. As shown in FIG. 12, the clutch block 154 is slidably guided vertically between the inner face of the removable plate 66 and the opposed front face of the driver bar 86. The clutch ball 156 is retained in an aperture in the clutch block 154 and normally, or in raised position, engages in a socket 160, provided in the opposed face of the driver bar 86, as shown in FIG. 16, so as to releasably connect the slide members 148 to the bar. Secured to the inner face of the removable front plate 66 there is a stop member or block 162 which the clutch block 154 contacts on downward movement of the latter, and when this occurs, the ball clutch member 156 is forced out of its socket 160 into a clearance socket 161 in plate 66 to disengage the slide members 148 from the driver bar 86. It will be seen that the stroke of the bending tools 150 is much longer than the stroke of the cutters 120, the bending tools, following the bending operation, carrying the component down to a point proximate the circuit board, as shown in FIG. 15. The upper ends of the slide members 148 are provided with inwardly directed connectors or tabs 153 that engage in a transverse slot 155, provided in the clutch block 154. It will be seen that the slide members 148 may move broadside toward and away from each other allowing the tabs 153 to move along the slot 155 without disengaging the slide members from the clutch block 154.

The forming block 151 is retractable and is normally positioned in the space between the legs 136 of the shear block mounting with the upper surfaces thereof coplanar. In order that the forming block 151 may be retracted out of the way of the actuator bar 86, the block is pivoted at 170 to the body rear plate 65 and has an upper arm 171 positioned to be received in a clearance slot 172 provided in plate 65. The upper arm 171 normally has the end 173 thereof against the rear face of the driver bar 86 and on predetermined downward movement of the driver bar 86 is adapted to engage in a vertical slot 174 in the driver bar for clearance to retract the forming block 151 to the position shown in FIG. 15. A spring 176 is adapted to retract the forming block 151 by way of a camming lever 178. As illustrated in FIG. 15, after the forming tools 150 have descended with the actuator bar 86 and performed their forming operation, the free end 177 of lever 178 engages the rounded upper cam surface 180 of arm 168 and cams the latter counterclockwise to retract the forming block. The forming block 151 is returned to normal position on the "up" stroke of the driver bar 86 when a cam surface 179, at the lower end of slot 174 engages and pivots lever 178 clockwise as shown in FIG. 12.

Carried by the driver bar 86 on the lower end thereof is a pair of laterally spaced driver members 182 to drive the wedged shaped triplets 46 into the holes 48 in the board 32. Lower end portions of the driver members 182 are provided with vertical slots 184 in their opposed side surfaces to receive and retain the bent down conductors 36 as the ends of the driver members 182 abut the triplets 46 and force the latter into the holes 48 in the circuit board 32. The driver members 182 are in the form of small rectangular plates and are secured, such as by means of screws, to a carrier block 188 which in turn is secured by screws to the lower end of the driver bar 86, FIG. 21. With reference to FIG. 3, it will be seen that the driver bar 86 is at the lower limit of its stroke with the result that the driver members 182 have driven the triplets 46 into the circuit board holes 48.

In accordance with one feature of the invention, the driver members 182 and the bending tools 150 are arranged to reciprocate in the same paths of travel or ver-

tical planes 152 so as to retain the bent down leads 36 and then insert them axially, and in order to obtain this relationship I provide for lateral displacement of the bending tools 150 by the driver members 182 when the latter function to insert the triplets 46. With particular reference to FIG. 2, it will be seen that lower end portions 192 of the slide members 148 are recessed to receive normally the driver members 182 and that the bending tools 150 extend beneath the lower ends of the driver members 182 in the upper or retracted positions of the tools. In addition to placing the tools 150 and driver members 182 in the same planes of vertical travel, the recesses reduce the thickness of the lower end portions 192 so that they may be displaced laterally by a flexing action, as illustrated in FIG. 3, to allow the driver members to pass unobstructed. In the bending tools 150, upwardly facing angular cams 193 are provided for cooperation with similar cams 195 provided on the lower ends of the driver members 182. An advantage of this is that the forming tools 150 hold the component conductors 36 in proper position until the driver members 182 descend to the component conductors 36 whereupon the component is transferred to the driver members as the latter spread the forming tools 150 apart, thus insuring accurate alignment of the triplets 46 with the circuit board holes 48. The slide members 148 are made of a resilient metal, such as, a resilient steel whereby the lower end portions 192 will spring back to their normal lead bending positions on the "up" stroke of the driver bar 86.

In FIGS. 12 and 13 is shown feed mechanism, actuated by and upon each stroke of the actuator bar 86 to feed the next belted component 34 onto the shear blocks 138 and forming block 151. This is an indexing mechanism which is actuated from the actuator bar 86 by the lever 178. The lever 178 is affixed to a rotatable shaft 191 to which is also affixed one end of a lever arm 194. Pivoted to the other end of the arm 194 there is a pawl 196 held in engagement with the teeth of one of the pinions 116 by a coil spring 198. The extended arm, as at 200, of the pawl 196 is for manual operation of the pinion 116, which is used to start the end of a new roll of belted components in mesh with the pinions 116. Preferably, a yieldable holder 202 on a lever 204 is biased by a spring 206 to engage between the teeth of the pinion 116 in the well known manner of indexing mechanisms. Although the above description refers to a single indexing mechanism, it is to be understood that each of the pair of pinions 116 is provided with such a mechanism and both mechanisms are operated by the spring 176 under the control of the driver bar 86. The actuation of the indexing mechanisms by the driver bar is hereinafter described in detail.

In order to provide for adjusting the distance between the cutters 133 and also between the forming tools 150 so as to adapt to the shearing and forming of different sizes of electronic components, I provide for yieldingly urging the cutters, forming tools and the plates 110 outwardly against the side plates 64 of the guide body 62. In these positions, the cutter slide members 120 and former slide members 148 are adjusted to their outer limits, corresponding to the largest size component of which the applicator is capable of handling. To urge the parts to the outermost positions, I provide a pair of leaf springs 208 which are received respectively in recessed areas 210 provided on opposite sides of the driver bar 86. As is shown more clearly in FIG. 21, the leaf springs 208 are bowed and are secured midway of their ends respectively to plates 212 which are apertured to slide toward and away from the sides of the driver bar 86. Extending through the driver bar 86 in the recessed areas 210 thereof are supporting pins 214 which project into apertures in the plates 212 for sliding support on the pins. The outer faces of the spring carrying plates 212 are in sliding contact respectively with opposed faces of the former slide members 148.

Screwthreaded into each of the body side plates 64 is an adjustment member or screw 216, the screws preferably being provided with hand operated knobs 218 for convenience. The inner ends of the screws 216 are in abutment with the movable plates 110 so that by turning the screws the plates 110 and therefore the cutter slides 120 and 148 may be moved inwardly against the opposition of the leaf springs 208. Affixed on and to each of the screws is a pinion 220 and engaging between the teeth of each pinion is a yieldable or retractable detent 222 that normally holds the adjustment screws 216 in adjusted positions. The spacing between the teeth of the pinions 220 and the lead of the adjustment screw threads may be calibrated in accordance with different known sizes of electronic components to be handled. When an adjustment of the positions of the cutters 133 and forming tools 150 is made, it is also necessary to change the former block 151 and the driver members 182. By removing the cover plate 68, access may be had to the former block 151 which may be readily replaced with a former of desired width and also the driver members 182 may be removed as a unit with their carrying block 188 and be readily replaced with another of desired size.

Operation

Assuming the operating parts to be in their normal or home positions, operation of the applicator is initiated by the closing of the switch 108, FIG. 1. This activates the solenoid valve 104 to supply pressurized air to the underside of the piston of air cylinder 26 whereby to pivot lever 92 and thrust the driver bar 86 downwardly. As the bar 86 moves downwardly, it carries therewith the cutters 133, through the clutch ball 124, and the forming tools 150, through the clutch ball 156 and also the driver members 182 which are rigidly secured to the lower end of the bar. Since the cutters 133 project below the forming tools 150, the cutters function first and in cooperation with the shear blocks 138 sever the component conductors 36 at the prescribed points, outwardly of the triplets 46 following which the clutch block 122 engages the stop shoulder 130. At this stage of the operation, the clutch ball 124 is opposite the recess 132 whereby the continuing downward movement of the driver bar 86 forces the clutch ball into the recess, thus disengaging the cutters 133 from the driver bar and as a consequence stopping the cutters.

The driver bar 86 continues downwardly, carrying the bending tools 150 therewith through the clutch ball connection 156, the tools respectively engaging and bending the leads 36 downwardly over the sides of the forming block 151 and at the same time forcing end portions of the conductors 36 into the vertical slots 149 in the bending tools, as shown for example in FIGS. 4 and 5. At about this time, the driver bar 86 has descended to the point where the forming block is released by the clearance slot 174 to allow spring 176, acting through lever 178 to pivot arm 168 and thus retract the forming block from the position shown in FIG. 14 to that of FIG. 15. Also, actuation of the lever 178 retracts the pawl 196 of the component indexing mechanism, FIG. 13, into the next notch preparatory to moving the feed pinions 116 one tooth. The bending tools 150 continue downwardly to a position where the lower ends thereof are proximate the printed circuit board, whereupon the clutch block 154 engages the stop 162, disengaging the bending tools 150 from the driver bar 86. The driver bar 86 continues downwardly and the cams 195 on the driver members 182 engage the cams 193 on the forming tools 150 and displace the tools laterally by flexing the resilient end portions 192 of the formers apart. Following displacement of the forming tools 150 the driver members 182 engage and drive the wedge shaped triplets 46 into the holes 48 in the board 32.

On the return stroke of the driver bar 86, the upward movement thereof pivots the lever 178 to return the form-

ing block 151 to normal position, shown in FIG. 12, and actuates pawl 196 which then rotates the pinions 116 to advance the next one of the belted components 34 onto the forming block 151 and shear blocks 138. As the driver bar 86 continues to move upwardly, the clutch ball 156 is first forced inwardly which couples the clutch block 154 to the bar, carrying the bending tools 150 therewith. Next, the clutch ball 124 is forced inwardly to couple the clutch block 122 to the driver bar 86 and the return operation is stopped by the return of the air piston of cylinder 26 to its "down" position with the applicator operating parts in the positions shown in FIG. 12. It will be understood that solenoid valve 104 is only open so long as the push button switch 108 is held closed, and that upon release of the switch, air escapes from bleed valve 106 so as to allow the piston return springs to move the piston of cylinder 26 to its retracted or "down" position.

Assume that for the above described operation the applicator was being used to apply a run of the larger size of component to a printed circuit board and that it is now desired to apply a run of smaller components to other boards. To adapt the applicator to apply the smaller components, it is first necessary to remove the front plate 68 and substitute for the former block 151, a block of the desired width and substitute for the removable unit 188, a unit having the driver members 182 in the desired spaced apart relationship, and then adjust the shear blocks 138 inwardly toward each other to the desired spacing therebetween. Also, by means of the knobs 218, the opposite ones of the corresponding pairs of cutter slide members 12 and former slide members 148 are moved closer together by one or more teeth on the pinions 226 to properly space the cutters 133 and forming tools 150 apart for cooperation with the substituted forming block 151, driver members 182 and adjusted shear blocks 138.

While I have shown and described the applicator in considerable detail, it will be understood that many changes and variations may be made therein without departing from the spirit and scope of the invention.

What is claimed is:

1. In a machine for bending a pair of leads of an electrical component and inserting the leads, a body having a guideway and a lower open end, a retractable anvil beneath the lower end of said body to support an electrical component having oppositely directed leads projecting respectively beyond and laterally of said anvil, a pair of laterally spaced apart slide members guided for vertical movement by said guideway, a pair of forming tools respectively carried by said slide members, said forming tools having normally raised positions above said anvil in straddling relationship therewith and movable downwardly to engage and bend end portions of the leads downwardly in substantially parallel relationship, stop means limiting downward movement of said forming tools to predetermined positions, a vertically movable operating member between said forming tools, a pair of laterally spaced apart driver members carried by said operating member and slidably guided respectively by the opposed faces of said slide members and movable respectively in paths aligned axially with the bent down end portions of the leads, said driver members having normally raised positions above the normally raised positions of said forming tools and movable downwardly to positions below the lower predetermined positions of said forming tools, said forming tools normally projecting laterally into the paths of downward travel of said driver members and mounted for displacement laterally outwardly of said paths, clutch means connecting said forming tools to said operating member and releasable by and upon the stopping of said forming tools at said predetermined positions by said stop means, and cam means on said forming tools and on said driver members cooperable following the stopping of said forming tools at said predetermined positions to displace said forming tools by the downward

movement of said driver members below the predetermined lower limits of travel of said forming tools.

2. A machine as defined by claim 1 wherein the forming tools are connected to the side members by outwardly flexible resilient arms.

3. A machine as defined by claim 1 wherein the forming tools have opposed faces vertically slotted for respectively receiving the leads.

4. A machine as defined by claim 3 wherein the driver members have opposed faces vertically slotted to respectively receive the leads and with the slots normally aligned with the corresponding vertical slots in the forming tools.

5. A machine as defined by claim 1 wherein the opposed faces of the slide members are recessed to slidably receive said driver members.

6. In a machine for severing, bending and inserting a pair of leads of an electrical component having abutment shoulders on the leads comprising a body having opposite side walls and a lower end, a pair of plates within said body in broadside spaced apart relationship, said plates respectively mounted on said side walls and adjustably movable toward and away from each other, a pair of laterally spaced apart shear blocks beneath the lower end of said body, said shear blocks to support therebetween an electrical component having oppositely extending leads resting on the blocks with the abutment shoulders inwardly of said blocks, a pair of laterally spaced apart cutter members slidably guided respectively against opposed faces of said plates, said cutter members having normally raised positions in shearing relation respectively with said shearing blocks, first stop means limiting downward movement of said cutter members, a retractable anvil normally positioned between said shearing blocks to support said leads inwardly of the lead shoul-

ders, a pair of laterally spaced apart forming tools positioned for vertical movement from raised positions above the raised positions of said cutter members to a lower limit of movement, second stop means to stop said forming tools at the lower limit of movement thereof, said forming tools positioned to straddle said anvil and bend end portions of the leads including the shoulders downwardly in substantially spaced parallel relationship, a vertically movable driver bar between said forming tools, a pair of laterally spaced apart driver members carried by said driver bar inwardly of said forming tools, said driver members normally in raised positions above said forming tools and movable downwardly to engage the leads, the limit of movement of said driver members being below the lower limit of movement of said forming tools, clutch means connecting said cutter members to said driver bar and disengaged by the stopping of said cutter members by the first stop means, clutch means connecting said forming tools to said driver bar and disengaged by the stopping of said forming tools by said second stop means, means operable to retract said anvil and actuated by the downward movement of said driver bar prior to engagement of said driver members with the lead shoulders, said forming tools normally projecting respectively into the paths of movement of said driver member, and outwardly displaceable to clear said driver members, and cam means on said driver members and on said forming tools to displace said forming tools by the movement of said driver members below said forming tools.
